Joseph Schoepe.
Maurice P. Flory

UNITED STATES PATENT OFFICE.

JOSEPH SCHOEPE, OF NEW YORK, N. Y.

PAPER-CUP-DISPENSING DEVICE.

Application filed April 1, 1922. Serial No. 548,601.

To all whom it may concern:

Be it known that I, JOSEPH SCHOEPE, a citizen of Germany, residing at New York, in the county of New York and State of New York, have invented certain new and useful Improvements in Paper-Cup-Dispensing Devices, of which the following is a specification.

This invention relates to improvements in dispensing devices and particularly to apparatus for delivering drinking cups of flat envelope form from a stacked supply.

The main object is to provide a device which will easily and instantly project a single cup at each operation.

Another purpose is to provide means for positively engaging the lowermost cup in the stack and prevent the extraction of more than a single cup at one operation.

A further aim is in the provision of means which may be adjusted to accommodate cups of any thickness without change in the construction.

These objects are attained by the novel construction and combination of parts, simple and inexpensive, hereafter described and shown in the accompanying drawing, forming a material part of this disclosure, and in which:—

Figure 1 is a front elevational view of a cup dispenser made in accordance with the invention.

Figure 2 is a vertical sectional view taken on line 2—2 of Figure 1.

Figure 3 is a bottom plan view of the same.

Figure 4 is a fragmentary sectional view, taken on line 4—4 of Figure 2.

The apparatus as shown consists of a rectangular container having elongated flat sides 10, a front wall 11 and rear wall 12 enclosing a space suited to receive the flat folded cups 13.

Said cups, as well known, resemble a small paper envelope, folded and pasted lengthwise on one side and having a tab 14 folded over the seamed side, also secured by paste or like adhesive.

The rear wall 12 may be extended at the top to constitute a tab 15 having a perforation 16 thru which a screw or the like may be passed in fastening the apparatus to a fixed wall.

The front wall 11 is secured by a hinge 17 to a stationary portion 18 and is provided

with a lock 19 having a spring catch engaging the cover or top 20 of the container.

A bottom plate 21 is fixed between the side walls and formed with it are side flanges 22, a similar flange 23 being at the rear. 60

This bottom is held in position by bolts 24, the same passing thru slots 25 in the side flanges, permitting vertical adjustment relative to the lower transverse edge of the fixed front plate 18. 65

The cups 13 rest upon the bottom plate 21 in compact stacked relation, when entered by releasing the front member 11, and are held firmly down by means of a weight 26 having a thickened front portion 27, its bottom being concave, as at 28. 70

The cups are guided by ribs 29 and 30, formed respectively in the front and rear walls 11 and 12, said ribs preventing catching of the edges of the cups and assuring a 75 smooth and uniform descent under the weight, which, by reason of its longitudinally curved bottom 28, has the effect of slightly bending the cups, presenting the flaps 14 in position to be engaged. 80

Fixed to the lower side of the plate 21 is a frame or guide plate 31 acting as a runway for a thin flat plate 32 having a narrowed front angular end 33, to the front face of which is attached a pusher plate 34, the same extending upward thru an opening 35 to engage the edge of the cup flap 14. 85

Fixed in the pusher 34 and plate 33 is the end of a rod 36 held in place by the nut 37, the other, rear end of the rod being flattened and pivotally connected by a bolt 38 midway in the length of a lever 39, one end of the lever being pivoted to clip bracket 40 and the other projected out thru a slot 41 in the side wall 10 into position to be readily 95 grasped by an operator.

This lever is held normally in a retracted position by a tension spring 42, connected at its ends respectively to the lever and a clip 43, as best shown in Figure 3. 100

In operation, the container having been supplied with the flat cups thru the door or wall 11, the latter is closed and then held by the spring lock.

Upon moving the lever 39 forward, motion 105 is conveyed to the pusher, which engaging the flap of the lowermost cup pushes it outward from over the plate 21, under the edge of the fixed wall 18, where it can easily be reached by hand. 110

Obviously due to the adjustment of the plate 21 different thicknesses of cups can be handled.

Having thus described my invention, what I claim as new and desire to secure by Letters Patent, is:—

A dispensing apparatus for flat paper cups having transversely folded edges near their front ends, said apparatus comprising 10 a container having a relatively low front wall, a spring locked front plate hinged to said wall, a bottom plate having raised flanged side edges containing slots, means passing through the slots for adjustably

securing the flanges within the side walls of 15 the container, a hook adapted to contact with the folded edge of the lowermost cup, vertical guides extending inwardly from the rear wall of the container and from said front plate, said guides making contact with the 20 folded cups, means for pressing the cups upon the surface of said bottom plate, a lever pivoted on said plate to move in a horizontal plane, a spring for retracting said lever, and an operative connection between 25 said lever and said hook.

In witness whereof I affix my signature.
JOSEPH SCHOEPE.
